KOH ONO, OF NEW YORK, N. Y.

DOLL.

1,377,623.

Specification of Letters Patent. Patented May 10, 1921.

Application filed June 3, 1920. Serial No. 386,154.

To all whom it may concern:

Be it known that I, KOH ONO, a subject of the Emperor of Japan, residing at New York city, New York, have invented certain new and useful Improvements in Dolls, of which the following is a clear, full, and exact description.

This invention relates to dolls and particularly to walking dolls, and a general object of the invention is to provide a simple, strong, durable and yet relatively inexpensive walking doll structure which is mechanically superior to prior walking dolls of its general type.

15 The prior art in walking dolls of the general type of that in which the present invention is embodied is represented by United States Letters Patent to C. J. Simonot, No. 507,174, October 24, 1893, which discloses the use of a lever or rocker member connecting and fulcrumed between the legs of the doll for effecting the alternate forward and backward movement of the legs. In a recent Patent No. 1,269,056, June 11, 25 1918, to Frank Criest, a pull rod was added to a walking doll of the Simonot type, the Criest doll operating otherwise in the same manner as the Simonot doll.

The present invention aims, both to simplify, to strengthen, and to render mechanically more effective the construction of walking dolls of the leg rocker type, and also so to construct such a doll that it will stand alone without special manipulation and careful balancing.

An important feature of the invention is the extension of the legs of the doll into proximity to the shoulders and neck and the location of one of the pivotal connections between the legs and the trunk or body proper in the region of the shoulders and neck. This feature is important in that it contributes to the maintenance of the center of gravity of the doll vertically above the area of the feet while yet providing sufficient freedom of relative movement of the parts to facilitate the walking movement. It will also further be noted that by this construction the center of gravity of those parts of the doll which are supported upon the legs is brought into proximity to the point of pivotal support upon the legs or the pivotal connection to the legs, whereby a slight movement of the body about the pivotal axis 45 does not tend to throw the center of gravity outside the supporting area of the feet.

Another important feature of the invention is the arrangement of the leg rocker at one side of the legs, whereby a natural separation of the legs is permitted and whereby greater freedom of relative movement of the parts is also permitted while at the same time the construction is simplified and its liability to get out of order is substantially eliminated.

Other important features and objects of the invention will appear from the following description and claims when considered in connection with the accompanying drawings, in which—

Figure 1 is a front elevation of a doll embodying the present invention;

Fig. 2 is a side elevation of the doll shown in Fig. 1, with the parts in walking position;

Fig. 3 is a side elevation on a reduced scale, with the parts in standing position;

Fig. 4 is a section on the line 4—4 of Fig. 2;

Fig. 5 is a section on the line 5—5 of Fig. 1; and

Fig. 6 is a sectional detail on the line 6—6 of Fig. 5.

The construction shown in the drawings is particularly adapted for the use of wood as the material from which the main parts of the leg and body structure are formed, the head and arms of the doll being preferably of ordinary composition construction. In the illustrated construction, the legs 2 are shown as formed of pieces of wood turned into cylindrical form and tapered at their lower ends to receive the feet 4, preferably also formed of wood and connected to the legs in any suitable manner as by dowels, not shown. At their upper ends, the legs 2 are cut away upon their outer sides to form rabbets or recesses 6 which receive the depending body side pieces 8, shown as rectangular in form and connected at their upper ends to a semi-cylindrical cross piece 10 upon which the head of the doll is to be mounted. The side frame or body pieces 8 may be attached to the shoulder or head support 10 in any suitable manner as, for example, by nails 12 driven through the side pieces into the cross piece.

Depending from the cross piece or head support 10, midway between the side pieces 8 and between the legs 2, is an intermediate body member 14 which is shaped, as shown in Figs. 2 and 3, to constitute a chest and

back for the doll body, and which also provides a support for the rocker pivot 16 upon which the leg operating rocker or lever 18 is fulcrumed, this fulcrum or pivot 16 being located, as shown in the drawings, near the front face or edge of the intermediate body member 14 and the rocker or lever 18 extending in front of and being connected to the front sides of the legs 2.

10 As shown more clearly in Fig. 5 of the drawings, the lever or rocker 18 is preferably formed by bending up a piece of wire to form an intermediate pivot receiving loop 20 substantially circular in outline and preferably somewhat larger than the pivot 16, the lever 18 at its ends being provided with elongated loops 22 which are connected to the fronts of the legs by straps 24 looped over one of the sides of the loops 22 and secured to the legs by any suitable means as, for example, by tacks 26.

The pivotal support for the legs is shown as comprising a pin 28 which may also be of wood and which extends through the body 25 side pieces 8 and through the intermediate body member 10, the legs being bored at 30 near their upper ends to receive the pin 28, the pin 28 being preferably somewhat smaller than the bearing openings 30 in the 30 legs to provide for an easy movement of the legs in walking, and also to provide for such movement of the body relative to the legs as is necessary to permit the legs readily to assume the standing position upon the 35 feet 4.

From an examination of Figs. 2 and 3 of the drawings, it will be noted that the doll's head 32 is provided with a shoulder or bust portion 34 shaped to fit over the curved 40 cross piece 10, the head being attached to this cross piece in any suitable manner, as, for example, by driving nails through the part 34 into the cross piece. It will also be noted from an examination of Fig. 1 that 45 the arms 36 are attached to the body substantially opposite the cross piece 10, a convenient method of attaching the arms being to drive nails 38 therethrough, the nails preferably passing through the body side pieces 8 and into the ends of the cross piece 10. Washers 40 may be provided between the heads of the nails 38 and the arms 36 to permit the arms to be turned into different positions with relation to the body, as shown in 50 Fig. 2 of the drawings.

As shown in Fig. 3 of the drawings, the head is preferably so located upon the shoulder or cross piece 10 that the center of gravity is slightly in front of the pivotal axis of the pivot pin 28, whereby the body tends to rock into position to press the rocker or lever 18 against the front faces of the legs 2. The principal advantage of placing the head in this position is that more of the 60 supporting surface of the feet 4 extends in

front of the vertical line through the pivot 28 than behind this line, and therefore with the center of gravity of the body of the doll thus located, there is not so much tendency for the doll to tip either backward or forward when placed on a slightly inclined surface. It will be understood, however, that even with the center of gravity of the body so located that there is a tendency to move the rocker lever 18 away from the legs 2 to 75 the limit provided by the strap loops 24, such dislocation of the center of gravity would have to be considerable to throw it outside the area of the feet 4 and to cause the doll to tip out of its standing position. 80 The center of gravity of the head and body together is so near the pivotal axis of the pivot 28, when the head is located upon the shoulder piece 10 in a natural position, that a considerable rocking movement of the 85 body about the axis of the pivot 28 must take place to throw the center of gravity outside of the supporting base of the feet 4 when the legs are in standing position.

To cause the doll to walk, the usual practice is to grasp the doll by the head, tip it very slightly backward, and then move it over the floor. This causes an alternate movement of the legs through the action of the lever or rocker 18, and one of the important advantages of the illustrated construction is that this movement is facilitated by having the point at which the propelling force is applied to the legs, that is, through the pivot 28, in relatively close 90 proximity to the point at which the doll is grasped to effect the walking movement. In prior constructions, the pivotal support of the legs has been so far from the head that a considerable leverage is exerted against 105 the hand by the reaction to the walking pressure, thus making it difficult for a small child to effect the walking movement of the doll. Furthermore, by extending the legs substantially to the shoulders of the doll or 110 in close proximity, as in the illustrated construction, and having the rocker member 18 located at considerable distance from the pivotal support of the legs, a considerable leverage is provided for transmitting the 115 walking movement through the rocker member 18 from one leg to the other. Moreover, by connecting the rocker loosely upon the fronts of the legs, freedom from binding, which characterizes prior constructions, is obtained, further freedom being obtained by elongating the pivot 16 so that the loop 20 which is preferably of considerably greater diameter than the pivot 16, may travel up and down the pivot as the 125 legs move alternately from one step position to the other step position.

From the foregoing description it will be seen that the present invention provides a doll construction of extreme simplicity, of 130

great structural strength, of high mechanical efficiency, and which, by reason of the construction and arrangement of the parts, will quickly assume a standing position without special manipulation or careful balancing, and which, moreover, will imitate more closely the walking action of a child than most constructions of the prior art, since the leg length tends to give the step length characteristic of a child of the height of the doll. The likeness to actual walking is also helped by the fact that the doll can stand alone before and after the walking movement.

Although the illustrated construction is one that is especially suited to manufacture with wood as the material, it will be understood that the invention is not restricted to the particular material from which the structure is made nor to the particular structural details and shapes herein illustrated and described.

Although the doll may be formed from various materials, the mechanism for effecting the walking movement of the legs is preferably so constructed as to be substantially noiseless. In the illustrated construction, for example, the pivot 16 is preferably formed of wood and the straps 24 may be formed of leather, cloth, or other suitable noise deadening material.

What I claim as new is—

1. A walking doll comprising a body, legs pivoted upon said body to swing thereon, a pivot intermediate between the sides of said body, and a lever fulcrumed on said pivot and slidably connected to each leg upon an outer face thereof at a point below the leg pivot.

2. A walking doll comprising a head support, legs, a pivot suspended from said head support upon which said legs swing, an intermediate member carried by said head support and having a pivot thereon, a lever fulcrumed upon said pivot, having its arms projecting over corresponding outer sides of said legs and slidably connected to each leg upon said side.

3. A walking doll comprising a head supporting cross piece, body side pieces depending from the ends of said cross piece, legs, a pivotal support for said legs extending between said side pieces, and upon which said legs are confined between said side pieces, an intermediate body member depending from said cross piece between said legs, and a leg-controlling lever fulcrumed on said intermediate member.

4. A walking doll having, in combination, a rectangular frame comprising an upper member shaped to receive the head of the doll, a lower member formed as a pivot to support the legs, and two side members connecting said upper and lower members, legs pivoted on said lower member between said side members, a leg separating member car-

ried by said frame between said legs, and a leg operating and controlling lever fulcrumed upon said separating member and pivotally connected to said legs.

5. A walking doll having, in combination, 70 a body frame, comprising a head supporting cross piece, arms and depending side pieces connected to said cross piece, legs, and a pivot carried by said side pieces upon which said legs are pivoted between said side pieces, 75 a lever pivotally and slidably connected to said legs upon outer faces thereof, and a member secured to said body frame, a pivot for said lever carried by said member and located so that the axis of the lever lies intermediate between the side pieces of said frame and is offset to one side of said legs in the direction of the walking movement thereof.

6. A walking doll comprising a body, a 85 head carried upon said body, legs pivoted upon said body to swing thereon in walking, a lever fulcrumed upon said body intermediate between the sides thereof and pivotally and slidably connected to said legs below the pivotal connection of the legs to the body, the lever being located at a distance from said connection greater than the distance between said connection and the upper limit of the body, and the legs being pivoted upon said body in such proximity to the shoulders that the distance from the pivot to the top of the head of the doll is very much less than the distance from the pivot to the surface upon which the doll 100 stands.

7. A walking doll, comprising a body, legs pivoted upon said body to swing thereon in walking and a lever fulcrumed on said body to swing on an axis located intermediate between the sides thereof and means for connecting the lever with an outer face of each of the legs constructed and arranged to allow lost motion between the lever and the legs but to limit positively the relative 110 movement thereof.

8. A walking doll, comprising a body and legs, said body comprising a pivot for each leg and a support for said pivot upon both the outer and the inner sides of said leg, 115 and a lever fulcrumed on said body to swing on an axis located intermediate between the sides thereof and having a slidable connection to each leg at a point in one of the outer faces of said leg lying substantially in the median plane through said leg normal to its pivot.

9. A walking doll, comprising a body, legs pivoted upon said body to swing thereon in walking, a lever fulcrumed on said body intermediate between the sides thereof and having its arms slidably connected to sides of said legs facing in the same direction, said slidable connections having positive limits of movement.

10. A walking doll comprising a body and legs, a pivot upon which said legs are confined between the sides of said body, a leg separating member carried by said body, a leg rocking lever fulcrumed upon said separating member and formed with elongated loops at its ends, and straps connecting said loops of said lever with outer faces of said legs.
- 10 11. A walking doll comprising a body, legs pivoted upon said body to swing thereon in walking, a lever, a pivot intermediate between the sides of said body and upon which said lever is free to rock about a vertical axis and upon which it may also slide vertically, and loop connections between the arms of said lever and an outer face of each leg.
12. In a walking doll comprising a body 20 and legs pivoted upon said body to swing thereon in walking, a lever bent up from wire and comprising an intermediate bearing loop, a pivot of sound-deadening material upon which said loop turns, said lever 25 also comprising elongated end loops, and sound-deadening material connected to the respective legs of the doll and loops through the respective end loops of said lever.
13. A walking doll comprising a head 30 supporting cross piece, body side pieces depending from the ends of said cross piece, legs located between said side pieces, an intermediate body member depending from said cross piece between said legs, a pivotal 35 support for each leg carried both by the adjacent side piece and by the intermediate member, and a leg controlling lever fulcrumed on said intermediate member and connected to the respective legs.
- 40 14. A walking doll comprising a head supporting cross piece, body side pieces de-
- pending from the ends of said cross piece, legs located between said side pieces, an intermediate body member depending from said cross piece between said legs, a pivotal support for each leg carried both by the adjacent side piece and by the intermediate member, and a leg controlling lever fulcrumed on said intermediate member and having a lost motion but positively limited 45 connection with an outer face of each of said legs.
15. A walking doll comprising a head supporting cross piece, body side pieces depending from the end of said cross piece, 50 legs located between said side pieces, a pivotal support for said legs extending between said side pieces, an intermediate body member separating said legs and through which said pivotal support also extends, and a leg controlling lever fulcrumed on said intermediate member below said pivotal support and having a loop and strap connection with an outer face of each of said legs.
16. A walking doll comprising a head 55 supporting cross piece, body side pieces depending from said cross piece, legs located between said side pieces, a pivotal support for said legs extending between said side pieces and upon which said legs are pivoted 60 substantially at their upper ends, an intermediate body member depending from said cross piece, separating said legs, providing a second support for the pivot of each leg and extending below said side pieces, and 65 a lever fulcrumed upon said intermediate body member below the leg pivots and having a lost motion but positively limited connection with an outer face of each leg.

Signed at New York city, N. Y., this 2nd day of June 1920.

KOH ONO.
